DOOR LATCH

Richard T. Anderson, Stacy, Minn.

Application June 21, 1944, Serial No. 541,344

7 Claims. (Cl. 292—163)

1

My invention relates to an improvement in door latch and deals more particularly with a latch of the handle type.

In recent years latches of the handle type have become increasingly popular. Most of these latches with which I am familiar are provided with a swingably mounted handle extending on both sides of the door and which is operable by a pull upon the handle on one side of the door and a push on the handle on the opposite side of the door. Certain difficulties have been found with this type of latch. The public has become so accustomed to the practice of turning a knob to open a door that occasionally considerable twisting strain is exerted against the door handle in an attempt to open the door. As the handles have been supported in such a manner that no twisting of the handle was permitted, occasionally a handle or its support will be broken by this twisting strain. Numerous latches have been replaced after being broken by a person attempting to open the door by twisting the handle rather than by pushing or pulling upon the same.

It is the object of the present invention to produce a latch of the handle type which may be operated either by a pushing or pulling action as above described, or which may be operated by a twisting movement of the handle. As a result the twisting force often exerted upon the door handles will not injure the operating mechanism thereof. A twisting action of the door handle in either direction will tend to unlatch the door and permit the same to be opened.

A feature of my invention lies in the provision of handles normally held in a selected position by resilient means. This handle is supported in a housing extending into the body of the door and is universally pivoted at one side of said casing. A latch bolt is freely connected to said handle at a point spaced from the universal pivotal support. The swinging of the handle in a horizontal plane acts to retract the normally projecting latch bolt from engagement with its keeper.

The universally supported handle is also provided with an arm or projecting means extending vertically both above and below the handle. This arm or projection is engageable with fixed fulcrum points on the latch casing. Rotation of the handle about its axis in one direction tends to cause one end of this arm or projection to engage its fulcrum and to slide the latch bolt out of engagement with its keeper. Pivotal movement of the handle about its axis in the opposite direction causes the other end of the

2

arm or projection to engage its fulcrum and to retract the latch bolt. Thus either pivotal movement of the handle about its transverse axis or a swinging movement of the handle in a horizontal plane will act to disengage the latch.

A feature of the present invention lies in the locking means employed to hold the latch bolt from retraction. The handle is connected to a slidable plate, which in turn is connected to the latching bolt to operate the same. This slidable plate is provided with a notch in one side thereof. A sleeve is engageable in this notch and in locked position of the door, prevents longitudinal movement of the plate. The sleeve is provided with a notch in one side thereof through which the plate may slide. Thus when the sleeve is in one rotative position the latch bolt may be retracted, while in any other rotative position the latch bolt is prevented from such rotation. A key is provided for rotating this sleeve and to thus lock or unlock the latch bolt.

The key construction comprises a novel feature of the present invention. The key is generally cylindrical to fit within the rotatable sleeve previously described. Angularly spaced grooves are provided in the cylinder to accommodate a predetermined key. The angular positions of the slots in the key must correspond with the angular positions of the projections in the sleeve in order to accommodate the key.

These and other objects and novel features of my invention will be more clearly and fully set forth in the following specification and claims.

35 In the drawings forming a part of my specification:

Figure 1 is a transverse section through a door and frame showing the position of the lock therein.

40 Figure 2 is a perspective view of the lock, portions of the casing thereof being broken away in order to show the internal construction thereof.

Figure 3 is a view similar to Figure 2 showing the handle in a different position.

45 Figure 4 is a view similar to Figure 3 showing the handle in another position.

Figure 5 is a perspective view of the latch showing the handle thereof in still a different position.

Figure 6 is a cross-sectional view through the latch mechanism.

Figure 7 is an elevational view of the exterior of the latch casing.

Figure 8 is an elevational view of the key.

Figure 9 is a diagrammatic view of the key and 55 its rotatable sleeve.

Figure 10 is a view similar to Figure 9, the view being taken at right angles to the view of Figure 9.

Figure 11 is a perspective view showing the manner in which the latch bolt housing it attached to the housing of the latch mechanism.

Figure 12 is a perspective view of the lock for holding the latch bolt mechanism from operation.

The latch A is designed to fit into a circular aperture 10 in a door B. A second aperture 11 extends from the free edge 12 of the door B into communication with the aperture 10 through the body of the door. The circular apertures 10 and 11 are designed to accommodate the circular casing of my latch. Obviously, however, the shape of the apertures may be changed to accommodate different styles of casings which may enclose the latch mechanism.

The latch A is housed in a hollow substantially cylindrical outer casing 13 having a closed end 14 and a circumferential flange 15 at its other end. The flange 15 may be attached to the cover plate 16 which extends over one face of the door B and the cover plate 17 overlying the opposite face of the door B. The cover plates 16 and 17 are held in proper position by any suitable means such as bolts 19. The cover plates 16 and 17 conceal the edges of the aperture 10 and the casing 13.

A substantially U-shaped handle 20 is provided with parallel handle ends 21 and 22 and a relatively straight center portion 23. Hollow socket like handles 24 and 25 are secured to the handle ends 21 and 22, as illustrated in Figure 1 of the drawings, these handles being held in place by bolts 26 or other suitable means.

Secured to the central portion 23 of the handle 20 I provide a disc or plate 27. This disc or plate is secured to the handle to rotate therewith. A portion of the disc or plate 27 is cut away to provide opposed notches 29 and 30. These notches 29 and 30 engage pivot pins 31 and 32, which will be later described in detail.

The cover plate 17 is provided with a center aperture 33 which forms a universal pivotal support for the handle 20. The closing end 14 of the housing is provided with an aperture therethrough sufficiently larger than the diameter of the handle to permit the swinging movement of the handle 20. The open end of the housing 13 is closed by a disc closure 34, best illustrated in Figures 6 and 7 of the drawings. This disc closure 34 is provided with angularly spaced arcuated flanges 35, 36, and 37 which engage within the hollow cylindrical casing walls 13 to hold the plate 34 properly spaced from the closed end 14 of the casing. The closure plate 34 is provided with an elongated slot 39 therein which permits swinging movement of the handle 20 about its fulcrum 33. The spring 40 is compressed between the central portion 23 of the handle 20 and the flange 37. This spring 40 is anchored to a projection 41 on the flange 37. The spring 40 is conical, and the small end thereof encircles a pin 42 on the handle 20 so as to hold the spring engaged between the handle and the flange 37. This spring 40 acts to normally hold the handle 20 in the position illustrated in Figures 1 and 2 of the drawings.

The closure plate 34 is held in proper position by means of the pivot pins 31 and 32. These pivot pins are headed and extend through the plate 34 and through the closed end 14 of the latch housing. The ends of the pins are threaded to accommodate nuts which act to hold the

closure plate 34 and the housing in assembled relation.

A plate 44 is slidable externally of the closure plate 34 and is provided with an elongated slot 45 therein through which the center portion 23 of the handle 20 extends. A similarly directed slot 46 is provided in the closure plate 34. A pin or bolt 47 extends through the slot 46 to connect the plate 44 with the inner end of the latch bolt 49. The outer end 50 of the latch bolt 49 is cam-shaped or wedge-shaped so that the latch bolt 49 may be retracted independently of the handle operation as the door swings closed.

The door frame 51 is provided with a keeper 52 therein of any suitable type, including a recess 53 into which the beveled or wedge-shaped end 50 of the latch bolt 49 may engage. As the door closes the beveled end thereof acts in the manner of a cam to retract the latch bolt until it aligns with the aperture 53, whereupon the bolt enters the aperture. A spring 54 encircles the latch bolt 49 and extends between a collar or sleeve 50 enclosing the end of the latch bolt and the outer surface of the casing 13. The latch bolt 49 is accordingly held in normally projecting position due to the action of this spring 54.

A sleeve 55 encloses the latch bolt 49 and serves as a guide therefor. This sleeve 55 is provided at its outer extremity with a flange 56 having apertures 57 therein through which screws may extend to hold the sleeve 55 in proper position with relation to the door B. As best illustrated in Figure 11 of the drawings, lips 59 are provided at the inner extremity of the sleeve 55, which lips are engageable in arcuated slots 60 in the casing or housing wall 13. This holds the sleeve 55 in proper position relative to the latch housing.

The plate 44 is provided with a notch 61 therein in one side thereof. A sleeve 62 is rotatably supported by the housing end 14 and the closure plate 34 and engages in this notch 61. The relative position between the sleeve 62 and the notch 61 may be best seen in Figure 7 of the drawings. As shown in Figures 9 and 10, the sleeve 62 is provided with a slot 63 in one side thereof of proper depth and in proper position to permit the plate 44 to slide therethrough. It will be obvious that when the sleeve 62 is in position so that the slot 63 is on the side of the sleeve next adjacent the plate 44, longitudinal movement of this plate may be effected. However, when the sleeve 62 is in any other rotatable position the plate 44 will be held from movement, thus preventing movement of the latch bolt 49.

As will be seen in Figures 9 and 10 of the drawings the sleeve 62 is provided with an enlarged diameter portion 64 which is positioned between the closure plate 34 and the housing wall 14, thus holding the sleeve from longitudinal movement.

This enlarged diameter portion 64 is provided with a groove 65 therein which extends approximately one-half the circumference of the enlarged diameter portion. Inwardly extending slots 66 are provided at each end of the groove 65. These slots 66 communicate with the hollow interior of the sleeve 62.

As illustrated in Figures 6, 9, and 10 of the drawings, one or more inwardly extending keys 67 are provided in the sleeve 62. These keys 67 are placed in various angular relations. The key 69, best illustrated in Figure 8 of the drawings, is provided with one or more key ways 70 to accommodate the keys 67. These key ways 70 are angularly spaced in the same manner that the keys 67 are angularly spaced, so that the proper

key may be inserted in the sleeve, but any other key would be excluded therefrom. Thus the key 69 must have slots or key ways 70 which match the positions of the keys 67 before the key may be inserted. The key 69 is provided with a flat head 71, by means of which it may be rotated. The key is also provided with an annular groove 72 for the purpose which will be hereinafter more fully set forth.

With reference now to Figures 6 and 12 of the drawings, it will be noted that spacer sleeves 73 and 74 encircle the pivot pins 31 and 32 between the closure plate 34 and the housing plate 14. A lever 75 is provided with a hollow journal 18 which encircles the sleeve 74 and is rotatably supported thereby. The free end of the lever 75 is provided with a finger 76 designed to extend through the slots 66 in the sleeve 62. A spring 77 is secured to the lever 75 and engages against the flange 36. The spring 77 normally tends to urge the finger 76 into engagement with one of the slots 66. This finger 76 engages the key 69 when the same is inserted into the sleeve 62. The edges of the slots 66 are beveled so that when the finger 76 is urged outwardly by the key, the inclined edge of the slot will act as a cam to force the lever 75 out of engagement with the slot, the finger 76 then riding against the base of the groove 65 until the other extreme position of the sleeve 62 is reached, whereupon the lever 75 will engage in the other notch 66. However, when the key 69 is not in place the lever 75 engages into the sleeve a distance sufficient to prevent rotation of the sleeve 62, thereby holding the sleeve in locking or unlocking position.

The operation of my latch will now be described. In installing the latch A in the door B, an aperture 10 is cut through the door and an aperture 11 is formed in the edge 12 of the door B communicating with the aperture 10. The housing 13 is inserted into the aperture 10, the holes are formed for the bolts 19. The sleeve 55 is then inserted through the aperture 11, the fingers 59 extending through the slots 60 in the casing wall 13. The spring 54 is then inserted in the sleeve 55 and screws or other fastening means are inserted through the holes 51 in the flange 56 to hold the sleeve 55 in proper position. The latch bolt 49 is then inserted through the sleeve 55 and through the spring 54. The bolt or pin 47 is then inserted through the plate 44 and the slot 46, this pin or bolt engaging into the end of the latch bolt 49. This pin or bolt 47 holds the latch bolt in proper position and holds the spring 54 more slightly compressed.

With the handles 24 and 25 removed from the U-shaped handle 20, the cover plates 16 and 17 are then threaded upon the handle ends 21 and 22 and the latch housing is secured in place by means of the bolts 19. The handles 24 and 25 are then attached in the manner illustrated.

The key 69 is then inserted in its sleeve 62 and the latch is in readiness for operation. The key 69 when fully inserted in the sleeve 62 engages the finger 76 of the lever 75 in a counter-clockwise direction as viewed in Figure 6. When supported in this position the sleeve 62 may be rotated in unison with the key, the key ways 70 and keys 67 holding the key and sleeve from relative rotation. The sleeve 62 is then rotated until the slot 63 is in registry with the adjacent edge of the plate 44. In this position of the sleeve 62, the plate 44 may be moved longitudinally.

In this position of the door, the door may be closed without actuation of the handle 20. The

cam end 50 of the latch bolt 49 engages the door frame and retracts the bolt 49 simultaneously, compressing the spring 54. When the latch bolt is in registry with the keeper aperture 53, the spring 54 urges the bolt into projected position, holding the door closed. The door may be opened by operating the handle in three different ways. Figure 3 of the drawings illustrates one of the three positions of the handle 20, which will act to retract the latch bolt. When the handle 20 is rotated about the axis of the straight portion 23 thereof in one direction, the notch 29 engages against the pivot pin 31. This pivot pin is fixed with respect to the latch casing and therefore rotation of the handle 20 acts to move the notch 30 away from its pivot bolt 32, the disc or plate 27 pivoting about the pivot pin 31 as a fulcrum. This action inclines the door handle, moving the same in the slot in a manner to compress the spring 40. The pivotal movement of the handle 20 is not sufficient to permanently change the shape of the spring 40 by engagement with the projection 42. This inclined movement of the handle 20 slides the plate 44 along the closure plate 34, acting through the pin 41 to retract the latch bolt 49, compressing the spring 54. Both the spring 40 and the spring 54 assist in returning the latch bolt and handle into normal position when the handle is released.

In the event the handle 20 is rotated in a direction opposite, the direction of rotation described in connection with Figure 3, the latch will assume the position illustrated in Figure 4 of the drawings. Twisting movement of the handle 20 in this case will cause the notch 30 to engage the pin 32, this pin acting as a fulcrum to separate the notch 29 from its pin 31 and to move the handle 20 longitudinally of the slot 39. This movement of the handle 20 moves the plate 44 longitudinally, acting through the pin 47 to retract the latch bolt 49, compressing the spring 54. The springs 40 and 54 cooperate in returning the handle and latch bolt into normal position.

In Figure 5 of the drawings, I disclose another handle movement which effects the retraction of the latch bolt. If the handle end 21 is pulled or if the handle 22 is pushed, the entire handle will swing about its fulcrum 33 into the position illustrated in Figure 5. In this event both of the notches 29 and 30 are withdrawn from their respective pivots 31 and 32, moving the handle 20 longitudinally of the slot 39. This action compresses the spring 40 and also acts to slide the plate 44 longitudinally, acting through the pin or bolt 47 to retract the latch bolt 49. The springs 49 and 54 again cooperate in returning the handle to normal position when released.

It will thus be noted that the latch may be opened by a swinging movement of the handle or by a rotative movement thereof in either direction. It will also be noted that in every event the handle and latch bolt will be returned to normal position by the springs 40 and 54. It should further be seen that the latch bolt 49 may move independently of the handle 20 by moving the latch bolt 49, the bolt 47 and the plate 44, the slot 45 being long enough to permit movement of the plate without moving the handle.

The groove 72 in the key 69 holds the key in position in the sleeve 62. The finger 76 of the lever 75 may engage in this notch when the key is partially inserted. In this position of the key the finger 76 is not retracted and the latch may be held either in locked or unlocked position, depending upon which slot 66 embraces the finger

16. To move the key longitudinally in either direction from this intermediate position requires the retraction of the lever 75 against spring tension. Thus the key is maintained in the sleeve 62 against accidental removal.

It will be noted that with the present lock it is extremely easy to insert the key in order to unlock the door. The key is inserted into the sleeve 62 which projects from the housing of my latch. The projecting end of this sleeve 62 is readily located by touch even when it can not be seen and the key may be readily inserted thereinto. Thus my latch may be easily locked or unlocked even in total darkness.

In accordance with the patent statutes, I have described the principles of construction and operation of my door latch, and while I have endeavored to set forth the best embodiments thereof, I desire to have it understood that obvious changes may be made within the scope of the following claims without departing from the spirit of my invention.

I claim:

1. A door latch comprising a casing, a handle extending through said casing, means pivotally supporting said handle for pivotal or swinging movement thereof, means on said handle spaced from the axis thereof engageable with said casing upon pivotal movement of said handle in either direction to cause a swinging movement of said handle, resilient means urging said handle to one extreme position, a slideable latch bolt, and a link having a slot therein through which the handle extends at a point on the handle spaced from said pivotal supporting means connecting said handle and said latch bolt.

2. A door latch comprising a casing, a handle extending through said casing, means pivotally supporting said handle for pivotal or swinging movement thereof, means on said handle spaced from the axis thereof engageable with said casing upon pivotal movement of said handle in either direction to cause a swinging movement of said handle, resilient means urging said handle to one extreme position, a link looped about said handle at a point spaced from said pivotal supporting means, the swinging movement of said handle sliding said link, and a slideable latch bolt connected to said link to move therewith.

3. A door latch comprising a casing, a handle extending through said casing, means pivotally supporting said handle for pivotal or swinging movement thereof, means on said handle spaced from the axis thereof engageable with said casing upon pivotal movement of said handle in either direction to cause a swinging movement of said handle, resilient means urging said handle to one extreme position, a barrel extending from said casing, a bolt slidably supported in said barrel, a link connected to said bolt and slideable therewith, said link having a slot therein encircling said handle at a point spaced from said pivotal supporting means.

4. A door latch comprising a casing, a handle extending through said casing, means pivotally supporting said handle for pivotal or swinging movement thereof, means on said handle spaced from the axis thereof engageable with said cas-

ing upon pivotal movement of said handle in either direction to cause a swinging movement of said handle, resilient means urging said handle to one extreme position, a bolt slidably supported by said casing, a link having a slot therein encircling said handle at a point spaced from said pivotal supporting means, and means pivotally connecting said link and said bolt.

5. A door latch comprising a casing, a handle extending through said casing, means pivotally supporting said handle for pivotal or swinging movement thereof, means on said handle spaced from the axis thereof engageable with said casing upon pivotal movement of said handle in either direction to cause a swinging movement of said handle, resilient means urging said handle to one extreme position, a bolt slidably supported by said casing, a link having a slot therein encircling said handle at a point spaced from said pivotal supporting means, and a pin pivotally connected to said link for connecting said link to said bolt.

6. A door latch comprising a casing, a handle extending through said casing, means pivotally supporting said handle for pivotal or swinging movement thereof, means on said handle spaced from the axis thereof engageable with said casing upon pivotal movement of said handle in either direction to cause a swinging movement of said handle, resilient means urging said handle to one extreme position, a bolt slidably supported by said casing, spring means normally urging said bolt in one direction, a link having a slot therein through which said handle extends at a point spaced from said pivotal supporting means, and a connecting pin connecting said link to said bolt.

7. A door latch comprising a casing, a handle connecting therethrough, means on said casing pivotally and swingably connecting said handle to said casing, means on said handle comprising a pair of spaced hooks oppositely disposed on opposite sides of the handle axis, means on said casing engageable in each of said hooks, said last named means limiting the swinging movement of said handle in one direction, spring means normally biasing said handle toward said limited position, a slideable latch bolt connected to said handle and slidably supported in said casing to slide upon swinging movement of said handle, and a link pivotally connected to said latch bolt and to said handle, said link having a slot therethrough through which said handle may extend at a point spaced from said pivotal supporting means.

55 RICHARD T. ANDERSON.
